E. F. HEISER,
CYLINDER REBORING DEVICE,
APPLICATION FILED MAY 24, 1915.

1,187,992.

Patented June 20, 1916.

UNITED STATES PATENT OFFICE.

EDGAR F. HEISER, OF KINGSTON, MISSOURI.

CYLINDER-REBORING DEVICE.

1,187,992.

Specification of Letters Patent. Patented June 20, 1916.

Application filed May 24, 1915. Serial No. 30,105.

To all whom it may concern:

Be it known that I, EDGAR F. HEISER, a citizen of the United States, residing at Kingston, in the county of Caldwell and

5 State of Missouri, have invented certain new and useful Improvements in Cylinder-Reborning Devices, of which the following is a full and exact specification.

This invention relates to devices for use 10 in metal-working, and particularly to tools and operating means therefor for truing out cylinders, such as engine cylinders, for which it is desired to provide efficient portable means in motor car shops for re-boring 15 such cylinders accurately and at the same time as speedily as possible. A device of this character is shown in Patent No. 1,097,318 which was issued to me on May 19, 1914, and the present invention relates to 20 improvements over the machine of that patent.

One object in view, therefore, is to provide means for properly centering the tool-carrying means within the cylinder, together 25 with an improved bearing construction for the tool-carrying shaft, and also a feed arrangement for said shaft whereby the latter may be quickly removed at the end of each operation.

30 It is a still further object to provide a bearing and feed construction whereby the parts may be assembled in proper axial alignment for operation on cylinders which are closed at one end.

35 With these and other objects in view, as will appear in the course of the description, the invention comprises various details of construction and combinations of parts as hereinafter described in connection with the 40 accompanying drawing which illustrates one embodiment of the invention which has been devised for carrying the same into practice; after which those features of my improvements which are deemed to be novel 45 will be severally specified in the appended claims.

In this drawing—Figure 1 is a perspective view of the device; Fig. 2 is a longitudinal sectional view of the same, illustrating the device in working relation to a cylinder and with the auxiliary bearing blocks in operative position; Fig. 3 is a section on the line III—III of Fig. 2 (on a larger scale); Fig. 4 is a view in partial 55 longitudinal section illustrating the device in working position in relation to a cylinder

which is closed at one end; and Fig. 5 is a transverse section through the shaft and tool-holder as constructed for the boring operation illustrated in Fig. 2.

In the drawing, the shaft 2 which carries the tool 4 with its tool-holder or block 6, is shown tubular in form and adapted to be received in smooth split bearings 8, 10, provided respectively in the somewhat similar 60 bearing bracket members 12 and 14, clamping screws 16 being provided for regulating the tightness of the bearings. At one end the shaft 2 is fitted with a suitable hand-wheel 18 or any other satisfactory means, such as a power attachment, if desired, for 65 imparting rotary movement to said shaft. Tapered auxiliary bearing blocks 20, 20, are provided for alining said shaft axially with the bore of the cylinder 22 to be operated 70 upon, as in the prior patent referred to. When the shaft 2 and its bearings have been adjusted by means of these temporary bearings 20 in the manner explained in said 75 patent, the bearing bracket members 8 and 10 are clamped in the proper position, as determined by said temporary bearings, by means of a pair of yoke rods 24, the transverse portion of each of which is adapted to be seated in one of the grooves 26 of the 80 member 10, the member 8 having similar grooves 26 for seating the tie bars 28 which are held in place by the clamp nuts 30 on the threaded ends of the rods 24.

The feeding movement of the shaft is obtained by providing one end of the shaft 90 with a bayonet slot 32 for receiving a pin 34 projecting from one section of a split nut 36, which latter is adapted for movement along the screw 38 and being held in 95 engagement therewith when the nut sections are clamped together by being received within the end of the shaft. The said screw 38 projects within the slotted end of the shaft 2 and has its outer end clamped by a 100 screw 40 in the head of a yoke member 42, the legs of which are held by suitable clamp screws 44 to opposite sides of the bracket member 10.

As will be observed from Fig. 5, the tool 4 105 fits within an axial bore 46 of the holder 6, and may be adjusted therein by means of a screw 48 fitted in the opposite end of said bore and abutting the inner end or shank of the tool, which is clamped in adjusted position by means of the set screw 50. The holder has a reduced shank portion adapted

to fit a transverse bore 54 through the shaft 2, which is provided with a threaded opening 56 for a screw 58 for clamping the latter in operative position. By means of this holder arrangement, the tool can be adjusted within the holder and the latter removed and reapplied to the shaft without disturbing the adjustment of the tool as first made.

- 10 In Fig. 4 is shown an arrangement adapting the device for use in connection with cylinders having one end closed so that it is possible to insert only one of the auxiliary bearing members 20 for centering the shaft 2. The bearing bracket members 8 and 10 must therefore be adjusted and clamped on the same end of the cylinder. This is done by assembling the parts as shown, with the plate portions of the bracket members 20 clamped directly together by the bolts 60 and their bearings 14 and 16 projecting in opposite directions and the bearing 14 extending within the base of the cylinder. The bracket member 10 is provided with 25 dowel pins 62 adapted to be received in openings 64 in the member 8 for axially alining the bearings 14 and 16, and bolts 66 serve to secure the member 10 to the cylinder. In this relation the parts are clamped together after the shaft 2 has been properly alined by means of one of the temporary or auxiliary bearing blocks 20 and the latter removed. In this use of the device, however, the yoke 42 is omitted and the feed screw 38 is passed through the spark plug opening of the cylinder where the plug 68 is suitably recessed as shown to receive the nut 36 and provided with the bayonet slot 32' for engagement with the pin of the said nut. The other end of the feed screw is secured to the tool block or holder which in this case is shown provided with a threaded socket to receive the end of the said screw. In operation on closed-end cylinders, it is necessary of course that the tool be mounted at the end of the shaft in order to be fed the full length of the cylinder, and for mounting the tool in this manner the holder is provided with a threaded shank 70 extending at right angles to the axis of the tool and adapted to be threaded into the socket 72 formed in one end of the shaft 2. By this means it will be clear that rotation of the shaft will carry it and the tool along the feed screw in the direction of the closed end of the cylinder.

From the foregoing the nature of the improvements and mode of operation of the same will be clearly understood. In the case of a cylinder open at both ends the shaft is centered by means of a pair of the blocks 20 inserted in the opposite ends of the cylinder, and the bearing members being thus properly positioned, are clamped by means of the yokes 24. The shaft can then

be withdrawn sufficiently to remove the blocks 20, and the tool-holder and tool are then applied to the shaft, which is then placed in operative position to bring the tool within the cylinder and the nut 36 in proper engagement with the slotted end of the shaft. After adjusting the tool properly, the shaft is rotated as usual to cut along the interior surface of the cylinder. It is obvious that after being fed entirely through the cylinder the shaft may be retracted by simply disengaging the same from the nut, and the nut reengaged at its former position along the screw and then re-applied to the shaft. The operation may then be repeated as often as may be necessary with the tool slightly advanced by adjustment of the screws 48 and 50. Moreover, where it is desired to operate successively upon cylinders of the same approximate diameter without materially altering the tool's adjustment, it is obvious that this may be done by simply removing the holder without unclamping the screws 58 and 50 while the shaft is being transferred from one cylinder to another and then refitting the holder to the shaft with the tool in the same relative position as before. It will also be observed that by use of the yoke arrangement for connecting the bracket members, a quick clamping construction is obtained which requires only the tightening of the nuts after the shaft has been centered; and also that the new feeding arrangement shown affords an improved bearing action because of both of the bearings for the shaft being left smooth.

The operation of the construction and arrangement illustrated in Fig. 4 is sufficiently indicated in the foregoing, the centering operation being similar to that stated excepting that but one temporary bearing block is used, and the arrangement of the bearings is modified as shown to meet the requirements of the closed-end type of cylinder, the use of the rods 24 being, of course, unnecessary in this relation. The yoke 42 is also dispensed with in the cutting operation, due to the mounting of the feed screw through the spark-plug opening, and the mounting of the tool is slightly modified in order to enable the cutting to take place at the extreme inner end of the shaft.

While the above represents what is now believed to be the preferred mode of practising the invention, the right is reserved to such formal changes and modifications as may fairly fall within the scope of the appended claims.

Claims.

1. A device for re-boring cylinders comprising, in combination, a cutter-carrying shaft, and means for feeding said shaft axially through the cylinder as the shaft is rotated, said feeding means including a nut

- having a detachable connection with one end of said shaft, said connection acting to hold said nut fixed against movement relatively to the shaft.
- 5 2. A device for re-boring cylinders comprising, in combination, a cutter-carrying shaft, and means for feeding said shaft axially through the cylinder as the shaft is rotated, said feeding means comprising a fixedly supported screw and a nut coöperating therewith, said nut having a detachable connection directly to one end of said shaft, said connection holding said nut and shaft fixed against relative movement.
- 10 3. A device for re-boring cylinders comprising, in combination, a cutter-carrying shaft, and means for feeding said shaft axially through the cylinder as the shaft is rotated, said feeding means comprising a coöperating screw and nut alined axially with said shaft, said nut and one end of said shaft being provided with a pin and open-slot connection permitting detachment of the shaft from said nut.
- 15 4. A device for re-boring cylinders comprising, in combination, a cutter-carrying shaft, and means for feeding said shaft axially through the cylinder as the shaft is rotated, said feeding means comprising a screw and a split nut coöperating therewith, said nut having a detachable connection with one end of said shaft, acting to hold the nut and shaft fixed against relative movement.
- 20 5. A device for re-boring cylinders comprising, in combination, a cutter-carrying shaft, means adapted to be positioned in the cylinder bore for alining said shaft axially therein, and additional means for feeding said shaft through the cylinder as the shaft is rotated, said feeding means having one element thereof provided with a detachable connection with said shaft, acting during the feeding operation to hold said element and shaft fixed against relative movement.
- 25 6. A device for re-boring cylinders comprising, in combination, a cutter-carrying shaft, means for alining said shaft axially in the cylinder, a feed screw, and a nut operable along said screw and detachably connected with one end of said shaft.
- 30 7. A device for re-boring cylinders comprising, in combination, a tubular cutter-carrying shaft, means for alining said shaft axially in the cylinder, a feed screw projecting into one end of the shaft and fixed against axial movement, and a nut operable along said screw and having a detachable connection with said shaft.
- 35 8. A device for re-boring cylinders com-

prising, in combination, a cutter-carrying shaft, means for alining said shaft axially in the cylinder, and means for feeding said shaft through the cylinder as the shaft is rotated, said feeding means including a split 65 nut provided with a detachable connection to one end of said shaft, adapted to hold said nut and shaft fixed against relative movement.

9. A device for re-boring cylinders comprising, in combination, a cutter-carrying shaft, a bearing for said shaft, means for alining said shaft and bearing members axially of the cylinder, a feed screw carried by said bearing and fixed against axial 70 movement, and a nut operable along said screw and having a detachable connection with said shaft.

10. A device for re-boring cylinders comprising, in combination, a tool-carrying 80 shaft, means for alining said shaft axially in the cylinder, a feed screw, and a split nut operable along said screw and having a detachable connection with said shaft, said shaft having a tubular portion adapted to 85 receive said nut and hold the latter in co-operative engagement with said screw.

11. A device for re-boring cylinders comprising, in combination, a cutter-carrying shaft, a pair of bearing brackets providing 90 smooth bearings for said shaft, means for alining said shaft and bearings axially of the cylinder, and a pair of yoke members connecting opposite ends of the brackets for clamping said brackets, when alined, against 95 opposite ends of the cylinder.

12. A device for re-boring cylinders comprising, in combination, a cutter-carrying shaft, a pair of bearing brackets providing smooth bearings for said shaft, means for 100 alining said shaft and bearings axially of the cylinder, a yoke member having its opposite leg portions secured to opposite sides of one of said brackets, a feed screw carried by said yoke member and adapted to be 105 presented axially of said shaft and bearings, and a nut operable along said screw and having a detachable engagement with the end of said shaft.

13. A device for re-boring cylinders comprising, in combination, a cutter-carrying shaft, having a bayonet slot at one end, and means for feeding said shaft axially through the cylinder as the shaft rotates, said feeding means comprising a feed screw and a 110 split nut operable along said screw, one of the sections of said nut being provided with a pin adapted for detachable connection with the slot of said shaft.

EDGAR F. HEISER.
